(57) **CLAIM**

The ornamental design for a headset, substantially as shown and described.

DESCRIPTION

FIG. 1 is a front perspective view of the headset, with the glasses in an in-use position.
FIG. 2 is a front view of the headset of FIG. 1, with the glasses in an in-use position.
FIG. 3 is back view of the headset of FIG. 1, with the glasses in an in-use position.
FIG. 4 is a right side view of the headset of FIG. 1, with the glasses in an in-use position.
FIG. 5 is a left side view of the headset of FIG. 1, with the glasses in an in-use position.
FIG. 6 is a top view of the headset of FIG. 1, with the glasses in an in-use position.
FIG. 7 is a bottom view of the headset of FIG. 1, with the glasses in an in-use position.
FIG. 8 is a back perspective view of the headset of FIG. 1, with the glasses in a social position.
FIG. 9 is a front perspective view of the headset, with the glasses in an in-use position, the sole difference being the elimination of the eye box from the design.
FIG. 10 is a front view of the headset of FIG. 1, with the glasses in an in-use position, the sole difference being the elimination of the eye box from the design.
FIG. 11 is back view of the headset of FIG. 1, with the glasses in an in-use position, the sole difference being the elimination of the eye box from the design.
FIG. 12 is a right side view of the headset of FIG. 1, with the glasses in an in-use position, the sole difference being the elimination of the eye box from the design.
FIG. 13 is a left side view of the headset of FIG. 1, with the glasses in an in-use position, the sole difference being the elimination of the eye box from the design.
FIG. 14 is a top view of the headset of FIG. 1, with the glasses in an in-use position, the sole difference being the elimination of the eye box from the design.
FIG. 15 is a bottom view of the headset of FIG. 1, with the glasses in an in-use position; and,
FIG. 16 is a back view of the headset of FIG. 1, with the glasses in a social position, the sole difference being the elimination of the eye box from the design.
The broken lines in FIGS. 1-16 are for illustrative purposes only and form no part of the claimed design or a specified embodiment thereof.
